UNITED STATES PATENT OFFICE.

CHARLES CRETORS, OF CHICAGO, ILLINOIS.

COVER-OPERATING MECHANISM.

1,309,565.

Specification of Letters Patent.

Patented July 8, 1919.

Application filed September 20, 1918. Serial No. 254,948.

To all whom it may concern:

Be it known that I, CHARLES CRETORS, a citizen of the United States of America, and a resident of Chicago, in the county of Cook, 5 State of Illinois, have invented certain new and useful Improvements in Cover-Operating Mechanisms, of which the following is a specification.

This invention relates to means for opening and closing the cover or lid of the popping pan of an automatically operating corn popping apparatus such as disclosed in my prior Patents No. 1,201,807, of October 17, 1916, and No. 1,279,663 of Sept. 24, 1918, 10 and has for its object:—

To provide a structural formation and association of parts in a cover operating mechanism by which the periodic opening and closing movements are attained at the proper time and in an effective and certain manner by an inter-controllable connection of the different units and so that when one mechanism ends an active operation it will release or start a succeeding mechanism from a normally inactive condition in which it had been positively maintained, all as will hereinafter more fully appear.

In the accompanying drawings:—

Figure 1, is a rear elevation of a corn popping apparatus, similar to that of my aforesaid patents, and having the present improvements applied.

Fig. 2, is an enlarged vertical section of the operating mechanism of the apparatus and the inter-controllable connections thereof.

Fig. 3, is a detail perspective view of the clutch operating head of the present mechanism.

Fig. 4, is a detail top plan of the mechanism shown in Fig. 2.

Fig. 5, is a sectional elevation on line x^5-x^5 , Fig. 2 showing the clutch operating mechanism and accessories in locked condition.

Fig. 6, is a similar view of the same in a released condition.

Fig. 7, is a detail horizontal section on line x^7-x^7 , Fig. 5,

Figs. 8 and 9, are companion detail side elevations of the cover raising mechanism, illustrating the same connected for an active popping operation and for an inactive or exhibition operation, respectively.

Like reference numerals indicate like parts 55 in the several views.

Referring to the drawings, 1 designates the tubular upright supporting post of the apparatus, carrying a horizontal tubular bracket sleeve 2 upon which is revolubly 60 mounted the fixedly connected fuel burner 3 and popping pan 4 of the apparatus and to which intermittent semi-revolutions are imparted by the automatically controlled mechanisms hereinafter described in detail. 65

4 designates the fixed top member or hood of the popping pan, of a truncated cone form and having a central top opening for the discharge of the popped corn, such opening having an associated lid or cover 5 adapted for operation by means hereinafter described. 70

6 designates a laterally disposed neck on the hood 4 for the introduction of a supply of raw corn into the popping pan 4 from a 75 supply hopper 7, as described in detail in my prior Patent No. 1,279,663, aforesaid.

8 designates a mutilated bevel gear wheel fixedly secured to the carrying hub of the fuel burner 3 and associated popping pan 4 80 aforesaid, and adapted to receive intermittent semi-rotation from a bevel pinion 9 on a constantly rotating countershaft 10 of the apparatus, as set forth in detail in my companion application for Letters Patent, Serial 85 No. 254,947. In the present improvement the upper end of the countershaft 10 has operative engagement with the cover raising and lowering mechanism hereinafter described in detail. 90

11 and 12 designate primary and secondary cam wings fixed on the gear wheel 8 in diametrically opposed relation, the primary wing 11 having a greater lift than the secondary wing 12 for the purpose hereinafter set forth. 95

13 designates the primary driving shaft of the apparatus receiving motion from a suitable power source, and operatively connected to the aforesaid countershaft 10 by 100 a pair of gear wheels 14 and 15, the gear wheel 15 having a cam formation 16 on its upper side for operative engagement with the timing mechanism of the apparatus.

17 designates a vertically movable head, 105 preferably arranged to slide upon the aforesaid countershaft 10, with a constant downward tendency under the influence of a

spring 17'. The upper end of said head is operatively associated with the carrying arm of the popping pan cover, as hereinafter described, while the lower end of said head 17 5 is adapted for serial operative engagements with the primary and secondary cam wings 11 and 12 aforesaid, and adapted in a fully raised condition to render the timing mechanism inoperative and at other times leave 10 said timing mechanism free for active operation, as set forth in detail in my companion application Ser. No. 254,947.

18 designates a bracket piece fixed on the upper end of the supporting post 1 and having 15 lateral overhanging arms for the pivoted attachment of the hub portion of the carrying arm 19 of the pan cover aforesaid.

20 designates a crank arm or stud on the aforesaid hub of the carrying arm 19 and 20 adapted for operative engagement with the movable head 17 and the timing mechanism associated therewith, and also with the locking means of the clutch operating head hereinafter described.

25 21 designates a crank arm on the cover carrying arm 19 adjacent to the hub thereof, and having operative connection by a rod or pitman 22 with an intermittently operating crank disk 31 hereinafter described.

30 23 designates a movable arm, or frame journaled on the pivot pintle of the cover carrying arm 19 with its rear end operatively connected to a corn measuring mechanism inclosed in the lower portion of the 35 supply hopper 7 aforesaid, by a connecting rod 24. At its forward end the movable arm 23 is formed for engagement with a latch piece 25 on the cover carrying arm 19 to lock the parts together for movement in 40 unison, and so that when said latch piece 25 is released the arm or frame 23 will remain inactive with a corresponding inactivity of the measuring mechanism aforesaid.

26 designates a spring bar or finger the 45 upper and free end of which is adapted for operative engagement with the hereinafter described clutch operating head, while its lower end is pivotally connected to a crank arm 27 on the hub portion of the cover carrying arm 19 aforesaid. In the present construction the spring finger 26 is maintained in proper position by a bearing stud 28 and a confining loop 29 on the arm or frame 23 aforesaid.

55 30 designates a worm hub supported on the upper end of the bracket piece 18 and encircling the upper end of the countershaft 10, with its worm formation in operative engagement with the gear teeth of the crank disk 31 heretofore referred to, and adapted to impart rotation thereto. The worm hub 30 has intermittent operative connection with the countershaft 10 by a T shaped key or clutch number 32 sliding vertically in a 60 keyway in said countershaft and having a

lateral lug 33 adapted to engage in a holding notch in the top of said worm hub 30 to lock the same to said countershaft for rotation therewith. The lateral lug 33 extends outwardly for operative engagement with 70 the hereinafter described automatically actuated clutch operating head, the action of which is to lift the clutch member 32 out of engagement with the worm hub 30, and to permit a reengagement of said parts at different periods in the operation of the apparatus. 75

34 designates a spring tending to force the clutch member 32 downwardly into engagement with the worm hub 30 aforesaid. 80

35 designates a cap piece associated with the upper end of the aforesaid countershaft 10 and having a depending sleeve extension surrounding said countershaft and having bearing in the bracket piece 18 aforesaid. 85 In the construction shown in Fig. 2 the cap piece 35 provides a bearing for the aforesaid worm hub 30 and an inclosure for the spring 34 above described.

36 designates an operating stem guided in 90 a vertical guideway in the bracket piece 18 and fixedly attached at its lower end to the vertically moving head 17 heretofore described. Intermediate its height the stem 36 is formed with a lateral shoulder 38 for intermittent operative engagement with the crank pin 20 of the cover-carrying arm 19 aforesaid, and the upper end of said stem 36 is adapted to engage and impart vertical movement to a cam block or rod formed and 95 arranged as follows:—

37 designates a cam block or rod arranged in vertical alinement with the operating stem 36 for intermittent operative engagement therewith. The upper end of the block or rod 37 is formed with a beveled or cam surface for operative engagement with a correspondingly formed lateral arm or formation of the clutch operating head now to be described:— 105

39 designates the hub portion of the clutch operating head above referred to, provided with a journal stem 40 turning in the bracket piece 18 in adjacent relation to the worm hub 30 and clutch member 32 aforesaid. 110

41 designates a curved clutch operating arm fixed transversely on the hub portion 39 and formed with a beveled or cam surface 42 adapted to be swung into the path of the lateral lug 33 of the clutch member 32, so 120 that in its circular travel with the countershaft 10, the said lug 33 may ride upon said cam surface 42 and thus lift said lug out of its operative engagement in the notch of the worm hub and the countershaft 10 125 aforesaid.

43 designates an operating pin or lug arranged on one end of the clutch operating arm 41 and adapted for operative engagement with the before mentioned spring fin- 130

ger 26, when the apparatus is run empty for exhibition purposes as set forth in the operation of the apparatus.

44 designates an operating pin or stud arranged near the opposite end of the clutch operating arm 41 and adapted for serial operative engagement with a pair of diametrically opposed cam lugs 45 on the periphery of the crank disk 31, and said cam lugs 45 are so positioned that as the pan cover 5 nears the end of its travel to its lowered position one cam lug 45 will engage and operate the pin 44 to swing the curved cam arm 41 into operative engagement with the clutch member 32 to release the worm hub 30 from its driving engagement with the countershaft 10 aforesaid. When the pan cover 5 nears the end of its travel to its raised position the other cam lug 45 will effect a similar clutch releasing operation.

46 designates a peripheral flange on the crank disk 31 against which the aforesaid pin 44 bears, and its movement in the manner above described is prevented, during the greater part of the semi-rotation of the crank disk 31, and until a cam lug 45 comes into operation when said movement is permitted by a gap formed in said flange adjacent to an individual cam lug 45. 47 designates a reciprocating rod guided by the pan cover and carrying arm 19 and receiving motion from the popped and expanded contents of the popping pan 4, as set forth in my aforesaid Patent No. 1,279,663. And as in said patented construction the outer end of the rod 47 is arranged adjacent to one end of the clutch operating arm 41 and is adapted to move the cam surface 42 of the arm 41 out of the path of the lateral lug 32 of the clutch member, so that the same may drop into clutching engagement with the worm hub 30 and cause positive rotation of the same and the crank disk 31 aforesaid.

48 designates a laterally arranged arm or projection on the hub portion of the clutch operating head above described, with its under surface beveled or inclined for operative engagement with the correspondingly beveled upper end of the cam block or rod 37 before described, and the arrangement is such that a complete upward movement of the cam rod 37 will swing the clutch operating arm 41, associated with said arm 48, out of the path of the clutch member 32 and permit operative engagement of the worm hub 30 with the driving countershaft 10 aforesaid.

49 designates a fixed collar on the journal stem 40 of the clutch operating arm 41 aforesaid, formed with a side ledge or flange 50 at its lower end, which ledge or flange is in turn formed with a central holding slot or passage 51, see Figs. 3, 5, and 6, adapted to receive a lateral pin 52 of the cam rod 37 to

lock the collar 49 and clutch operating arm 41 from a turning movement. At other periods in the operation of the apparatus, the pin 52 is moved vertically out of the slot 51 and is adapted to rest upon the ledge 50 when the clutch operating arm 41 and said collar 49 are turned to bring said legs 50 beneath the pin 52, as set forth in detail in the operation of the mechanism.

The operation of the apparatus is as follows:

Assume the popping pan 4 to be in a normal popping position with the pan cover 5 moving from an open position shown in dotted lines, to a closed position shown in full lines in Fig. 1, under the influence of the worm hub 30 and crank disk 31. In such downward movement of the cover 5, the corn measuring means is operated by the connecting rod 24, operatively associated with the cover carrying arm 19, to supply a charge of raw or unpopped corn to the popping pan 4. Coincident with the movements just described, the crank arm 20 of the cover carrying arm 19 acts against the shoulder 38 of the operating stem 36 to impart an upward movement to the same, and which in turn imparts a like movement to the cam rod 37 to lift its lateral pin 52 out of the slot 51 and thereby release the clutch operating arm 41 from the locked condition in which it was held by the engagement of said pin and slot.

Owing to the connection of the operating stem 36 with the vertically moving head 17, a like upward movement will be imparted to the head 17 to render the timing mechanism of the apparatus inoperative, as set forth in detail in my companion application Serial No. 254,947.

With the pan cover 5 nearing the closed position as above set forth, an adjacent cam lug 45 of the crank disk 31 comes into operative engagement with the pin 44 of the clutch operating arm 41 to swing the cam surface 42 thereof into the path of the clutch member 32 to lift the same out of driving engagement with the worm hub 30, so that further rotation of the cover operating crank disk 31 will be stopped, and at the same time the ledge or flange 50 will move beneath the lateral pin 52 to hold the same out of its locking engagement with the slot 51, above set forth.

The described parts now remain in an inactive condition until the corn in the popping pan 4 has reached the properly popped stage to operate the rod 47 as set forth in my prior Patent No. 1,279,663. With a movement of said rod 47 the same acts against the clutch operating arm 41 to swing the cam surface 42 thereof out of the path of the clutch member 32 and permit the same to effect a driving engagement with the worm hub 30, to in turn attain a semi-

revolution of the crank disk 31 and a lifting movement of the pan cover 5 to an open position. Near the end of such cover lifting movement another cam lug 45 on the 5 crank disk 31 has engagement with the pin 44 of the clutch operating arm 41 to swing the cam surface 42 thereof into the path of the clutch member 32 and lift the same out of driving engagement with the worm hub 30 so that further rotation of the crank disk 31 will be stopped and the pan cover 5 will be left in its raised position. At the same time the ledge or flange 50 will be turned from beneath the lateral pin 52, permitting the same to descend into the slot 51 to lock the clutch operating arm 41 against accidental movement.

In the described lifting movement of the pan cover 5, the crank arm 20 of the cover carrying arm 19 moves away from the operating stem 36 and permits the same and the connected head 17 to move downward so as to release the timing mechanism of the apparatus and restore the same to an active condition. In its downward movement the movable head 17 moves down onto the primary cam wing 11, on which it rests until released from such supporting engagement by a timing mechanism operating in unison with the present automatic cover moving mechanism, and preferably of the detail construction set forth in my companion application Serial No. 254,947 aforesaid.

With such release of the primary cam from the head 17 operative connection is reestablished between the bevel pinion 9 and the gear wheel 8 to effect a semi-revolution of the said gear wheel and a corresponding 40 semi-revolution of popping pan 4 into inverted or dumping position.

During such semi-revolution of the parts, the secondary cam wing 12 carried by said gear wheel 8 operates to move the head 17 into a raised position and retains such head in such raised position until the timing mechanism heretofore referred to, effects a releasing movement between said secondary cam wing 12 and the head 17 and reestablishes operative connection between the driving bevel pinion 9 and the mutilated bevel gear wheel 8 to cause a succeeding semi-revolution of the gear wheel 8 and a return of the popping pan 4 to an upright or 55 popping position. During such last mentioned semi-revolution of the bevel gear wheel 8 the primary cam wing 11 comes into action to effect a maximum upward movement of the head 17, associated operating stem 36 and cam rod 37 and thereby attain a vertical movement of the lateral pin 52 out of the slot 51, leaving the clutch operating arm 41 free to receive a turning movement, and then in the final upward movement of said parts an

operative engagement between the beveled upper end of the cam rod 37 and the beveled under surface of the arm 48 to move the clutch operating arm 41 out of engagement with the clutch member 32, so that the same may move down and operatively engage the worm hub 30, and through the crank disk 31 effect the closing movement of the pan cover 5 with which the present description of the operation of the apparatus began.

In the present structure the frame 23 is connected to and moves in unison with the cover carrying arm 19 in the normal operation of the apparatus. When it is desired to have the apparatus run empty for the purpose of exhibiting a continuous automatic operation of the mechanism without any feeding or popping of the corn, the frame 23 is disconnected from the cover carrying arm 19 so that said frame may move by gravity into an inactive position shown in Fig. 9, and in so doing the frame 23 brings the spring finger 26 into operative relation to the clutch operating arm 41. The spring finger 26 now lies in the path of the pin 43 of said clutch operating arm 41 and is adapted to disengage said clutch operating arm from its engagement with the clutch member 32 immediately following the heretofore described engagement of said clutch operating arm 41 with the clutch member 32 and which had been attained by a cam lug 45 of the crank disk 31 in the cover closing movement of said crank disk. In such operation the spring finger 26 performs the function of the push rod 47, which in an exhibition operation remains wholly inactive owing to the absence of corn in the popping pan. In the construction shown and described the spring finger 26 is in operative relation to the pin 43 only, when the cover carrying arm 19 is in its lowered position.

Having thus fully described my said invention what I claim as new and desire to secure by Letters Patent, is:—

1. A cover operating mechanism for corn popping apparatus, comprising a supporting frame, a swinging cover carrying arm pivoted on said frame, a crank disk journaled on said frame and having operative connection with said carrying arm, said crank disk having a pair of diametrically opposed cam formations near its periphery, a driving countershaft, means for imparting constant rotation to said countershaft, a worm hub journaled loosely on said countershaft and having operative engagement with said crank disk, a clutch connection between said hub and countershaft, intermittently operated means for moving the movable member of said clutch connection into operative engagement with said worm hub, and means operatively associated with the cam forma-

tions of the crank disk for moving said movable clutch member out of engagement with said worm hub, substantially as set forth.

- 5 2. A cover operating mechanism for corn popping apparatus, comprising a supporting frame, a swinging cover carrying arm pivoted on said frame, a crank disk journaled on said frame and having operative connection with said carrying arm, said crank disk having a pair of diametrically opposed cam formations near its periphery and a gapped holding flange associated with said cam formation, a driving countershaft, 10 means for imparting constant rotation to said countershaft, a worm hub journaled loosely on said countershaft and having operative engagement with said crank disk, a clutch connection between said hub and countershaft, intermittently operated means 15 for moving the movable member of said clutch connection into operative engagement with said worm hub, and means operatively associated with the cam formations of the 20 crank disk for moving said movable clutch member out of engagement with said worm hub, substantially as set forth.

3. A cover operating mechanism for corn popping apparatus, comprising a supporting frame, a swinging cover carrying arm pivoted on said frame, a crank disk journaled on said frame and having operative connection with said carrying arm, said crank disk having a pair of diametrically opposed cam 30 formations near its periphery, a driving countershaft, a worm hub journaled loosely on said countershaft and having operative engagement with said crank disk, a clutch connection between said hub and countershaft, 35 an operating head carrying a transverse arm provided with a clutch operating cam surface and with an operating pin at one end adapted for engagement with the cam formation of the crank disk to release the 40 clutch connection of the worm hub and countershaft, and a rod receiving intermittent motion from the corn popping mechanism and having engagement with the clutch operating head to effect an engagement of 45 the worm hub and countershaft, substantially as set forth.

4. A cover operating mechanism for corn popping apparatus, comprising a supporting frame, a swinging cover carrying arm pivoted on said frame, a crank disk journaled on said frame and having operative connection with said carrying arm, said crank disk having a pair of diametrically opposed cam formations near its periphery, 55 a driving countershaft, a worm hub journaled loosely on said countershaft and having operative engagement with said crank disk, a clutch connection between said hub and countershaft, an operating head carry-

ing a transverse arm provided with a clutch 65 operating cam surface and with an operating pin at each end, a rod receiving intermittent motion from the corn popping mechanism and having engagement with the clutch operating head to effect an engagement 70 of the worm hub and countershaft, and a frame separate from and capable of fixed connection to the cover carrying arm and carrying a spring finger adapted when said frame is attached to the cover carrying 75 arm to have operative engagement with one of the pins of the clutch operating head to effect a clutch engagement of the worm hub and countershaft, the other pin of said operating head being adapted for engagement 80 with the cam formation of the crank disk to effect a release of the clutching engagement of said worm hub and countershaft, substantially as set forth.

5. A cover operating mechanism for corn popping apparatus, comprising a supporting frame, a swinging cover carrying arm pivoted on said frame, a crank disk journaled on said frame and having operative connections with said carrying arm, said 85 crank disk having a pair of diametrically opposed cam formations near its periphery, a driving countershaft, a worm hub journaled loosely on said countershaft and having operative engagement with said crank 90 disk, a clutch connection between said hub and countershaft, an operating head carrying a transverse arm provided with an operating pin at one end and with a clutch 95 operating cam surface and a beveled operating face, a rod receiving intermittent motion from the corn popping mechanism and having engagement with the clutch operating head to effect an engagement of the 100 worm hub and countershaft, the said operating pin being adapted for engagement with the cam formations of the crank disk to effect a release of the clutching engagement 105 of the worm hub and countershaft, and an intermittently moving cam rod the 110 upper end of which is adapted to engage the beveled operating face of the clutch operating head to effect a clutching engagement of the worm hub and countershaft, 115 substantially as set forth.

6. A cover operating mechanism for corn popping apparatus, comprising a supporting frame, a swinging cover carrying arm pivoted on said frame, a driving countershaft, a worm hub journaled loosely on said countershaft and having operative connection with the cover carrying arm adapted to effect a rising and lowering motion of said arm, a clutch connection between said worm hub and countershaft, a clutch operating head controlling said clutch connection and receiving periodic actuation from the mechanism of the apparatus, and means for lock-

ing said operating head and associated clutch connection against accidental movement during an unclutched condition of the worm hub and countershaft, substantially as set forth.

7. A cover operating mechanism for corn popping apparatus, comprising a supporting frame, a swinging cover carrying arm pivoted on said frame, a driving countershaft, a worm hub journaled loosely on said countershaft and having operative connection with the cover carrying arm to attain a rising and lowering motion of the same, a clutch connection between said worm hub and countershaft, a clutch operating head controlling said clutch connection and receiving periodic actuation from the mechanism of the apparatus, a ledge or shelf associated with said operating head and formed with a vertical slot, a cam rod adapted to impart a turning movement to said operating head and provided with a lateral pin adapted to have supporting engagement on said ledge or locking engagement in said vertical slot, and a crank arm on the cover carrying arm having operative connection with said cam rod, substantially as set forth.

8. A cover operating mechanism for corn popping apparatus, comprising a supporting frame, a swinging cover carrying arm pivoted on said frame, a driving countershaft, a worm hub journaled loosely on said countershaft and having operative connection with the cover carrying arm to attain a rising and lowering motion of the same, a clutch connection between said worm hub and countershaft, a clutch operating head controlling said clutch connection and receiving periodic actuation from the mechanism of the apparatus, a ledge or shelf associated with said operating head and formed with a vertical slot, a cam rod adapted to impart a turning movement to said operating head and provided with a lateral pin adapted to have supporting engagement on said ledge and locking engagement in said vertical slot, a crank arm on the cover carrying arm having operative connection with said cam rod, and a vertically movable head having operative engagement with said cam rod, substantially as set forth.

Signed at Chicago, Illinois, this 16th day of September, 1918.

CHARLES CRETORS.
